UNITED STATES PATENT OFFICE.

CHARLES WILLIAM SIEVERT, OF LOS ANGELES, CALIFORNIA.

OIL-BURNER.

SPECIFICATION forming part of Letters Patent No. 716,121, dated December 16, 1902.

Application filed January 2, 1902. Serial No. 88,122. (No model.)

To all whom it may concern:

Be it known that I, CHARLES WILLIAM SIEVERT, a citizen of the United States, and a resident of Los Angeles, in the county of Los Angeles and State of California, have invented 5 a new and Improved Oil-Burner, of which the following is a full, clear, and exact description.

This invention relates to a device for burning oils, particularly the heavy oils, such as crude petroleum, and comprises certain novel features of construction by which I am enabled effectively to gasify the oil and mix it with air, so as to obtain thorough combustion.

15 This specification is a specific description of one form of the invention, while the claims are definitions of the actual scope thereof.

Reference is to be had to the accompanying drawings, forming a part of this specification, 20 in which similar characters of reference indicate corresponding parts in both the views.

Figure 1 is a sectional view of the invention, and Fig. 2 is a plan view with parts broken away.

25 a indicates the structure or inclosure in which the burner is held or placed. This may, for example, be a fireplace or the walls of a stove or any other device in connection with which the burner is used.

30 b indicates the base-plate of the burner, and this is constructed with an enlarged central opening b' for the passage of the air upward from below the base-plate. Mounted on the base-plate is an annular cup c, which is concentric to the opening b' and has radially-disposed troughs c' running across its central portion and lying over the opening b'.

35 d indicates the oil-supply pipe, which passes from below the base-plate but through the opening b' and communicates with the troughs at their point of juncture, so that the oil in passing from the pipe d falls into the troughs c' and thence down these troughs into the cup c at various points along the same. According to the construction here shown there 45 are four troughs, and the oil flow is thus divided into four streams running into the cup at equidistant points.

40 e indicates a cap which fits in the cup c and is supported by legs e', resting on the bottom of the cup, as shown. This cap e incloses the central portion of the cup and the troughs.

The air-draft passes through the opening b' and up into the cap e and is then deflected 55 downward into the cup c. To start the burner,

a quantity of oil is ignited in the cup c, and as this burns it will highly heat the adjacent parts, particularly the cap e. The flow of oil from the pipe d is now turned on, and as this oil passes by the highly-heated cap e and 60 into the cup c it is vaporized and simultaneously mingled with the air, which becomes heated by contact with the parts c, c', and e. This vapor may be ignited and burned in the cup c. As the operation of the burner goes 65 on the parts will become still further heated, and thus the most effective generation of gas and mixture of air therewith is obtained.

The burner may be used in innumerable connections, as will be apparent to persons 70 skilled in the art.

Various changes in the form and details of my invention may be resorted to at will without departing from the spirit of my invention. Hence I consider myself entitled to all 75 forms of the invention as may lie within the intent of my claims.

Having thus described my invention, I claim as new and desire to secure by Letters Patent—

80 1. A burner, comprising an annular cup having a central opening and provided with a plurality of upwardly-inclined troughs leading from the inner edge of the cup to the center of the opening thereof, and with which, at their point of juncture, a fuel-supply pipe is adapted to be connected, and an inverted cup-shaped cap provided with legs resting upon the bottom of the cup and supporting the cap above the central portion of the cup 90 with its lower edge extending into the same, as set forth.

2. A burner, comprising an annular cup having a central opening and provided with a plurality of upwardly-inclined troughs leading from the inner edge of the cup to the center of the opening thereof and with which, at their point of juncture, a fuel-supply pipe is adapted to be connected, and an inverted cup-shaped cap supported above the central 95 portion of the cup with its lower edge extending into the same, as set forth.

In testimony whereof I have signed my name to this specification in the presence of two subscribing witnesses.

CHARLES WILLIAM SIEVERT.
